US0D1068194S

(12) **United States Design Patent** (10) Patent No.: **US D1,068,194 S**
(45) Date of Patent: ** Mar. 25, 2025

(54) **CLEANING BRUSH**

(71) Applicant: **Yanping Wang**, Shenzhen (CN)

(72) Inventor: **Yanping Wang**, Shenzhen (CN)

(**) Term: **15 Years**

(21) Appl. No.: **29/953,049**

(22) Filed: **Jul. 18, 2024**

(51) LOC (15) Cl. 07-05

(52) U.S. Cl.

USPC **D32/52**

(58) **Field of Classification Search**

(57) **CLAIM**

The ornamental design for a cleaning brush as shown and described.

DESCRIPTION

FIG. 1 is a perspective view of a cleaning brush showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view showing the cleaning brush in use.

The broken lines shown in FIG. 9 depict the environment and form no part of the claimed design.

1 Claim, 9 Drawing Sheets
